UNITED STATES PATENT OFFICE.

WALTER F. KOKEN, OF ST. LOUIS, MISSOURI, ASSIGNOR TO KOKEN BARBERS' SUPPLY COMPANY, OF ST. LOUIS, MISSOURI, A CORPORATION OF MISSOURI.

BARBER-POLE.

1,178,732.

Specification of Letters Patent. Patented Apr. 11, 1916.

Application filed March 22, 1915. Serial No. 16,833.

To all whom it may concern:

Be it known that I, WALTER F. KOKEN, a citizen of the United States, residing at St. Louis, Missouri, have invented a certain new and useful Improvement in Barber-Poles, of which the following is a full, clear, and exact description, such as will enable others skilled in the art to which it appertains to make and use the same.

10 This invention relates to revolving barber poles, and has for its main object to provide a barber pole of novel design which is driven by an electric motor.

Another object is to provide an ornamental revolving barber pole that is equipped with a plurality of electric lights and a motor-driven, intermittent switch for causing said lights to flash or light up in a certain sequence, the motor that actuates said switch also being used to operate the rotatable member of the pole. And still another object is to provide an illuminated revolving barber pole that can be manufactured cheaply and which is so constructed 25 that the lights, the motor, the intermittent switch and the driving mechanism are completely protected from the weather.

Other objects and desirable features of my invention will be hereinafter pointed out.

Figure 1 of the drawings is a front elevational view of a revolving barber pole constructed in accordance with my invention. Fig. 2 is a horizontal sectional view taken on the line 2—2 of Fig. 1. Fig. 3 is a horizontal sectional view taken on the line 3—3 of Fig. 1. Fig. 4 is a vertical sectional view taken on the line 4—4 of Fig. 1. Fig. 5 is an enlarged vertical sectional view taken on the line 5—5 of Fig. 4. Fig. 6 is an enlarged horizontal sectional view taken on the line 6—6 of Fig. 4; and Fig. 7 is a diagrammatic view illustrating the wiring and the intermittent switch.

45 My improved barber pole preferably consists of a rotatable member provided with conventional barber pole stripes, an electric motor and mechanism coöperating with the motor for driving said rotatable member.

50 Means is preferably employed for illuminating the rotatable striped member of the pole, and in the preferred form of my invention as herein shown the pole is equipped with a plurality of electric lights and also with an intermittent switch for causing said lights

to flash or light up in a certain sequence, the switch that controls said lights being operated by the same motor that drives the rotatable striped member of the pole.

Referring to the drawings, which illustrate the preferred form of my invention, A designates a rotatable member provided with conventional barber pole stripes, B designates an electric motor for operating said member and C designates a plurality of electric lamp bulbs, preferably of different colors, that are arranged above the rotatable member A. The member A is preferably tubular-shaped and is arranged in a vertical or upright position inside of a glass housing 1 that is combined with two horizontally-disposed supporting members 2 and 3 arranged at the upper and lower ends of the glass housing 1, respectively, and which are provided with brackets 4 that are connected to a supporting structure by means of fastening devices 5, as shown in Fig. 4. The supporting members 2 and 3 are preferably of octagonal shape in outline, as shown in Fig. 1, and the bottom member 3 is provided with an annular groove for receiving the lower end of the glass housing 1 that incases the rotatable member A of the pole, said annular groove being of sufficient dimensions to receive a ring 6 of packing material so as to prevent injury to the glass housing 1 and also form a tight joint between said housing and the bottom supporting member 3, thereby preventing dirt and water from entering the casing D on the underside of the member 3 in which the electric motor, the intermittent switch and the operating mechanism are incased. The upper end portion of the transparent housing 1 projects into an opening in the top supporting member 2 and it is held securely in position by means of a plurality of non-metallic devices 7 that bear upon the upper edge of the glass housing 1, and thus press it downwardly against the bottom supporting member 3 and also hold the upper edge portion of said housing out of direct contact with the top supporting member 2, said devices 7 being preferably formed of cork, rubber or some other suitable material that has more or less resiliency. The devices 7 are held in engagement with the upper edge of the glass housing 1 by means of a cross piece 8 in the top supporting member 2 that is retained in position by means of fastening 105

devices 9, as shown in Fig. 5, that pass through the cross piece 8 and spacing devices 10, and whose lower ends are tapped into lugs 11 on the member 2.

5 A frame that is arranged inside of the
casing D carries the motor B, the intermittent
10 switch for controlling the electric lights
C, and the mechanism for transmitting
movement from the motor to the rotatable
member A and to said switch, said frame be-
ing detachably connected to the member 3
15 by means of fastening devices 12, and pref-
erably consisting of three castings, a, b and
c, that are detachably connected together,
as shown in Fig. 4, and which are provided
20 with horizontally disposed portions 13 in
which the various shafts of the operating
mechanism are journaled. The motor B is
mounted on the horizontally-disposed por-
tion 13 on the intermediate casting b, and
25 the shaft of said motor is provided with a
worm 14 that meshes with a worm gear 15
on a vertically-disposed shaft 16 which is
provided with a gear 17 that meshes with a
gear 18 on a vertically-disposed driving
30 shaft 19. The upper end of the driving
shaft 19 is connected to a spider 20 at the
lower end of the rotatable member A, thus
serving to support the member A, as well as
impart rotary movement to same. At the
35 upper end of the member A is a spider 21
provided with a center opening which re-
ceives a guiding member 22 that projects
downwardly from the cross piece 8 carried
by the top supporting member 2.

The electric light bulbs C at the upper end of the pole are mounted in lamp sockets 23 in a box 24 which is provided at its lower end with a horizontally-disposed portion 24^a which bears upon lugs 25 that project inwardly from the top member 26 of an ornamental cap E that incases the top supporting member 2 and the various parts carried by said member 2. The cap E is preferably tapered and of octagonal shape in general outline, and at the lower edge of same is an octagonal-shaped flange e that telescopes over the top supporting member 2. The top piece 26 of the cap E is provided at its lower edge with an octagonal-shaped flange e' that telescopes over the upper end portion of the cap E, and said top piece 26 is also provided with an annular-shaped flange e² that receives a transparent globe 27 that incases the lamp bulbs C, the rim or annular flange e² of the top member of the cap E being provided with one or more adjustable fastening devices 28 for holding the globe 27 in position. The top piece 26 is held firmly clamped against the upper edge of the cap E, and the cap as an entirety is held securely clamped to the top supporting member 2 by means of bolts 29 that pass through the cross piece 8 and through the inwardly-projecting lugs 25 on

the part 26, said bolts also serving to retain the lamp bulb box 24 in operative position, as shown clearly in Figs. 4 and 5. The depending guide 22 that passes through the center opening of the spider 21 at the upper end of the rotatable member A preferably consists of a piece of pipe that carries an electric light bulb 30 which is arranged inside of the rotatable member A, so as to illuminate said member, the member A being formed from paper or some other suitable material that is more or less transparent. The upper end of the pipe 22 is screwed into the cross piece 8 and is held securely in position by means of a set screw 31, as shown in Fig. 5. The casing D at the lower end of the pole is detachably connected to the bottom supporting member 3, and the top and bottom supporting members 2 and 3, respectively, are connected together by means of long through bolts 32, shown in Fig. 3, which pass through pieces of tubing 33 that are interposed between the members 2 and 3, as shown in Fig. 1.

The wires 34 from the electric lamp bulbs C lead downwardly through one of the pieces of tubing 33 to binding posts 35 that are provided with spring contacts 36 which form part of an intermittent switch that comprises a rotatable member 37 equipped with a wiper 38, as shown in Fig. 7, that engages the contacts 36 intermittently when the member 37 is rotated. The rotatable member 37 of said intermittent switch is carried by a vertically disposed shaft 39, which is provided at its lower end with a gear 40, shown in Figs. 4 and 7, that meshes with a pinion 41 on the lower end of the driving shaft 19, thereby causing the movable member 37 of the switch to rotate continuously when the motor B is in operation. A spring contact 42 that always remains in engagement with the rotatable member 37 of the intermittent switch is connected to a short conductor 43 that leads back to the negative side of the supply circuit S, as shown in Fig. 7, the positive side of said supply circuit being connected with the electric lamp bulbs C, and the lamp bulb 30 that is arranged inside of the rotatable member A of the pole being connected in multiple with the supply circuit S, as shown in Fig. 7. A switch S' is arranged in the motor circuit, as shown in Fig. 7, so as to control same, and a switch S² is arranged in the supply circuit at a point beyond the switch S', so as to enable the lighting circuit to be opened and closed without affecting the motor circuit. During the day the switch S² is left open so that the electric lights will not burn, but at night the switch S² is left closed so that the light 30 on the inside of the rotatable member A of the pole will burn continuously, and thus illuminate same, and the different colored

lights C will flash or light up intermittently in a certain sequence, and thus attract attention to the pole. The rotatable member 37 of the intermittent switch is insulated from the shaft 39 which carries same, and said shaft and the various spring contacts that form part of the intermittent switch are mounted on the sectional supporting frame arranged on the inside of the casing D, the wire that leads from the electric lamp bulb 30 also being incased in the piece of tubing 33 that incases the wires 34 that lead from the electric lamps C.

A barber pole of the construction above described presents a neat and ornamental appearance, as it comprises a constantly rotating member A provided with conventional barber pole stripes that is arranged inside of a glass housing that is surmounted by an ornamental cap E which carries a large, ball-shaped globe 27 in which a plurality of electric lights are arranged. Said electric lights are preferably of different colors, and at night, when the switch S² is closed, said lights flash intermittently in a certain sequence, and thus attract attention to the rotatable striped member A of the pole, which is also illuminated. The casing D at the lower end of the pole incases the motor, the intermittent switch and the driving mechanism, and thus completely protects said parts from the weather and prevents dirt from accumulating on same, and the ornamental cap E at the upper end of the pole prevents dirt and water from getting inside of the glass housing 1 or the rotatable striped member A that is arranged inside of same.

A barber pole of the construction above described requires practically no attention except to open and close the switches S' and S² that control the motor circuit and the lighting circuit, respectively, and such a pole can be manufactured at a low cost, owing to the fact that most of the metal parts of same consist of castings that can be quickly assembled and securely connected together with a few screws or bolts, the long through bolts 32 that pass through the tubular-shaped spacing members 33 serving to connect the top and bottom supporting members 2 and 3 together and the cross piece 8 of the top supporting member 2 co-operating with the yielding devices 7 that are interposed between same and the upper edge of the glass housing 1 to securely hold said glass housing in position without liability of cracking same. The ornamental cap E telescopes over the top supporting member 2 and is securely connected to same by means of two bolts 29 that also serve to connect the two parts of said cap together and also to retain the lamp socket box 24 in operative position.

Having thus described my invention, what

I claim, and desire to secure by Letters Patent, is:

1. A barber pole provided with a housing, a stationary member arranged at the upper end of said housing, an ornamental cap provided with a tapered portion and with a portion that is telescoped over said stationary member, a globe holder telescoped over the upper end portion of said cap, a cross piece on said stationary member, and fastening devices that pass through said cross piece and globe holder so as to retain the cap in position and secure the globe holder to same. 75

2. A barber pole provided with a housing, 80 a stationary member arranged at the upper end of said housing, an ornamental cap telescoped over said stationary member, a globe holder telescoped over said cap, a cross piece on said stationary member, an electric lamp holding device carried by said globe holder, and means for detachably connecting said lamp holding device and said globe holder to said cross piece. 85

3. A barber pole provided with a supporting structure that comprises a transparent housing and an ornamental cap surmounting said housing and consisting of telescoped sections, a stationary member that carries said cap, an electric lamp-holding device carried by said cap, and fastening devices that hold the parts of the cap together and also secure said lamp-holding device to said stationary member. 90

4. A barber pole provided with two horizontally-disposed supporting members that are adapted to be connected to a supporting structure, a transparent housing arranged between said members, a cross piece on said top member that extends transversely across 105 said housing, resilient devices on said cross piece that bear upon the upper edge of said housing and clamp it in position, an ornamental cap telescoped over said top supporting member, a globe carried by said cap, a lamp socket supporting member arranged inside of said globe and carried by said cap, devices that secure said lamp socket supporting member to said cross piece and thus clamp said cap in position, a rotatable, 110 striped member arranged inside of said transparent housing, an electric motor and an operating mechanism carried by said bottom supporting member for actuating said striped member, and a depending device 115 120 on said cross piece that centers said striped member.

5. A barber pole comprising horizontally-disposed top and bottom supporting members arranged one above the other, a transparent housing resting on the bottom member, a cross piece detachably connected to said top member and extending transversely across said housing, yielding clamping devices on said cross piece that bear upon the 125 130

upper edge of said housing and thus clamp it in position, a rotatable, striped member arranged inside of said housing, a driving shaft that supports said striped member, a 5 depending centering guide on said cross piece which projects into an opening in a co-operating guiding element at the upper end of said striped member, an ornamental cap piece telescoped over the top supporting 10 member and detachably connected to said cross piece, a casing detachably connected

to the bottom supporting member, and mechanism arranged inside of said casing and carried by a frame on said bottom supporting member for actuating said driving shaft. 15

In testimony whereof I hereunto affix my signature in the presence of two witnesses, this 18th day of March 1915.

WALTER F. KOKEN.
